ATTORNEYS

UNITED STATES PATENT OFFICE.

WALTER WHITTEN, OF SCHENECTADY, NEW YORK.

ELECTRICAL HEATER.

Application filed November 15, 1923. Serial No. 674,944.

To all whom it may concern:

Be it known that I, WALTER WHITTEN, a citizen of the United States, and a resident of Schenectady, in the county of Schenectady and State of New York, have invented a new and Improved Electrical Heater, of which the following is a full, clear, and exact description.

This invention relates to a new and improved form of electric heater which makes use of the action of eddy currents in a substantially solid core of preferably magnetic metal or material.

Another object is to provide means whereby the heat generated in a substantially solid core of metal is most efficiently transmitted to a circulating medium to be heated.

A further object concerns the provision of means whereby the most efficient transmission of the heat is effected.

The invention is illustrated in the drawings, of which—

Figure 1 is a sectional view through one form of the heater;

Fig. 2 is a horizontal section taken on the line 2—2 of Fig. 1;

Fig. 3 is a sectional view through a modified form of heater;

Fig. 4 is a horizontal section taken on the line 4—4 of Fig. 3;

Fig. 5 is a sectional view through a still further modified form of heater;

Fig. 6 is a horizontal section taken on the line 6—6 of Fig. 5;

Fig. 7 is a side elevation of a still further modification of heater;

Fig. 8 is a horizontal section taken on the line 8—8 of Fig. 7;

Fig. 9 is a plan view of a modified form of core;

Fig. 10 is a diagram of the circuit connection to the coil; and

Fig. 11 is a diagrammatic representation of a modified form of the circuit connection.

The forms of the invention shown in the drawings are preferred forms, although it is understood that other modifications in the construction and arrangement of the parts and in the character of the materials used may be adopted without departing from the spirit of the invention as set forth in the appended claims.

In general, the invention contemplates the provision of a substantially solid core of metal provided with passages therein for the flow of a fluid to be heated. These pas-

sages are suitably connected to a circulating system. The core is intimately associated with a winding to which alternating current of any desired frequency is supplied. The result of the rise and fall of flux in the metal of the core is the production of eddy current in the core which produces heat, and this heat is transmitted to the fluid moving through the passages.

In the form of the invention shown in Fig. 1 a core of metal 1 is provided. This core is provided with detachable plates 2 and 3. Through the core in the plates there is formed a tortuous passage 4 having straight portions lying in the core 1 and bends such as 5 formed in the plates 2 and 3. By removing the plates the straight portions of the passage can be cleaned out. The ends of the passages are connected to pipes 6 and 7 which may lead to any suitable circulating system. Disposed around the core 1 and the plates 2 and 3 is a sheet 8, preferably of insulating material, and wrapped around this sheet is a coil 9 to which an alternating potential is applied. The rise or fall of flux produced in the core will cause eddy currents which will heat up the core and, consequently, heat up the fluid flowing through the passage 4.

In Fig. 3 a similar passage is provided on the core, and the same sort of a winding is provided; but the upper end of the core is snugly embraced by an enclosing casing 10, and the upper end of the passage 4 opens into the casing, as shown at 11, 12 and 13, and the casing itself is provided with a plurality of discharge apertures such as 14. This construction is provided in case the fluid to be heated is a gas, and the discharge apertures 14 may be connected by suitable pipe (not shown) to various parts of the circulating system.

In Fig. 5 a central core 15 is formed and provided with vertically extending passages 16. This core is surrounded by a cylindrical shell 17 also provided with passages 18, and the central core and the shell are connected by upper and lower perforated rings 19. A winding 20 surrounds the central core, and the eddy current produced in this central core causes heat and transmits itself throughout the entire magnetic frame thus produced.

In Fig. 7 a rectangular magnetic frame 21 is provided having a central crosspiece 22 on which a coil 23 is mounted.

In Fig. 9 I show a solid core through which a plurality of large passages such as 24 are provided, and in each of these passages there are disposed a plurality of 5 small pipes such as 25. Through the large passages a liquid or gas can be passed to be heated, and in the small pipes either a gas or a liquid may be passed, so that two kinds of circulating fluid can be heated at the 10 same time.

In Fig. 10, 26 designates the magnetizing coil, and by having taps leading from said coil to a switch a greater or lesser part of the coil can be brought into circuit.

15 In Fig. 11 the diagram shows three separate sections of a coil 27, 28 and 29 each connected by separate switches to the circuit.

It will be understood that I have provided a simple and efficient type of heating 20 device whereby the heat effect of eddy currents is most efficient and may be used in a

plurality of ways for the generation of heat in a circulating medium.

What I claim is:—

1. An electrical heater which comprises a central, substantially solid core having vertically extending passages therethrough, a cylindrical shell surrounding said core, said shell having vertical passages extending therethrough, upper and lower perforated 30 plates connecting the core with the shell, and an alternating current winding surrounding said core.

2. An electrical heater which comprises a central substantially solid core having vertically extending passages therethrough, a cylindrical shell having vertical passages extending therethrough, upper and lower plates connecting the core with the shell and an alternating current winding surrounding 40 the core.

WALTER WHITTEN.
